UNITED STATES PATENT OFFICE.

WILLIAM HARVEY O'HARA, OF GREENVILLE, MISSISSIPPI.

STALK-CUTTER.

1,249,178.

Specification of Letters Patent. Patented Dec. 4, 1917.

Application filed August 10, 1917. Serial No. 185,547.

To all whom it may concern:

Be it known that WILLIAM H. O'HARA, a citizen of the United States, residing at Greenville, in the county of Washington and State of Mississippi, has invented certain new and useful Improvements in Stalk-Cutters; and he does hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in a stalk cutter adapted to be attached to the felly of an ordinary wagon wheel.

The invention comprises a simple and efficient device of this nature having various details of construction, combinations and arrangements of parts, which will be herein-after fully described, shown in the accompanying drawings and then specifically defined in the appended claims.

My invention is illustrated in the accompanying drawings which, with the letters of reference marked thereon, form a part of this specification and in which:

Figure 1 is a side elevation showing the application of my invention to a wagon wheel.

Fig. 2 is a top plan view.

Fig. 3 is a large detail in section through one of the cutter carrying shoes, and

Fig. 4 is a sectional view on line 4-4 of Fig. 3.

Reference now being had to the details of the drawings by letter:

A designates the felly of a wagon wheel with a tire B thereon. Shoes, each designed by letter D, are formed on the arc of a curve and each is recessed as at E upon its inner face and adapted to fit over the felly of the wheel. Bolts F are passed through registering apertures in the walls of the recess and serve to securely hold the shoes upon the rim

of the wheel. The outer convexed edge of each shoe is provided with transverse dove-tailed recesses. The inner ends of the cutting blades I have their opposite faces inclined and adapted to conform to the inclination of the walls of the recesses in which they are held. Each blade has a beveled portion K. Screws L pass through each shoe and engage the inner edges of the blades I, in the manner shown in Fig. 4 of the drawings; thus insuring the blades being securely anchored to the shoe.

By the provision of a stalk-cutter, embodying the features of my invention, it will be noted that shoes may be easily attached to or removed from the ordinary wagon wheel and utilized for the purpose of cutting stalks into short lengths of convenient size to be plowed underneath the ground.

What I claim to be new is:

1. In combination with a wagon wheel, a shoe having a concaved recess receiving the tire and rim, bolts passing through opposite walls in the shoe and engaged with the inner marginal edge of the rim of the wheel to hold the shoe in place thereon, the outer convexed edge of the shoe having transverse slots, blades fitted in said slots and projecting beyond the opposite faces of the shoe.

2. In combination with a wagon wheel, a shoe having a concaved recess receiving the tire and rim, bolts passing through opposite walls in the shoe and engaged with the inner marginal edge of the rim of the wheel to hold the shoe in place thereon, the outer convexed edge of the shoe having dove-tailed slots, blades with inclined faces fitted in said slots, said blades projecting beyond the opposite faces of the shoe, and means passing through the shoes for holding the blades in place.

In testimony whereof I hereunto affix my signature in presence of two witnesses.

WILLIAM HARVEY O'HARA.

Witnesses:

T. B. VAN NORMAN,
W. W. RICHARDSON.
